UNITED STATES PATENT OFFICE

GEORGE J. MEUER, OF MILWAUKEE, WISCONSIN, ASSIGNOR TO CUTLER-HAMMER, INC.,
OF MILWAUKEE, WISCONSIN, A CORPORATION OF DELAWARE

ELECTRIC SWITCH

Application filed December 13, 1929. Serial No. 413,736.

This invention relates to improvements in electric switches, and more particularly to improvements in electric switches of the slide button type.

- 5 An object of the invention is to generally improve and simplify the details of construction of the switch parts to facilitate assembly thereof, and to render such switches more trustworthy in operation.
- 10 Another object is to provide novel means for insulating the wiring terminals of the switch.

Another and more specific object is to provide stationary and movable contacts of novel 15 form together with improved switch actuating means.

Other objects and advantages of the invention will hereinafter appear.

The accompanying drawings illustrate certain 20 embodiments of the invention which will now be described, it being understood that the embodiments illustrated are susceptible of modification in certain details thereof without departing from the scope of the appended claims.

In the drawings, Figure 1 is a top plan view of a single circuit controlling switch constructed in accordance with my invention.

Fig. 2 is a vertical sectional view, on the line 2—2 of Fig. 1,—the contactor and the terminal screws being shown in elevation.

Fig. 3 is a perspective view, in separated relation, of the switch parts shown in Figs. 1 and 2,—the insulating barrier members having been omitted for clarity of illustration.

Fig. 4 is a top plan view of a so-called "three-point" or multiple circuit controlling switch constructed in accordance with my invention.

40 Fig. 5 is a vertical sectional view, on the line 5—5 of Fig. 4,—the contactor and terminal screws being shown in elevation.

Fig. 6 is a perspective view, in separated relation, of the switch parts shown in Figs. 45 4 and 5,—the insulating barriers being omitted; and

Fig. 7 is a perspective view of one of the insulating barrier members or wiring shields.

Referring first to the embodiment illustrated in Figs. 1 to 3, the numeral 10 design-

nates in general a sheet metal frame or housing of substantially inverted channel shape, said housing having a top wall 11 provided with extensions or lugs 12 and 13 which are preferably perforated in the manner indicated at 14 and 15 to provide for securement of the housing to a suitable support. The substantially parallel side walls 16 and 17 of said housing are provided at the lower edges thereof with integral lugs 18 and 19.

55 Wall 11 of the housing is provided with a rectangular perforation 20, the side walls of said perforation being adapted to guide and the end walls thereof being adapted to limit the reciprocating movement of the projecting portion 21^a of the actuating slide button 21.

60 The movable contactor 22 of the switch preferably comprises a convex or hemispherical bridging head 22^b and a substantially cylindrical shank 22^a. The bowed leaf spring member 23 is provided with a perforation to accommodate the shank 22^a,—an integral upwardly extending flange surrounding said perforation to strengthen the spring 65 at this point and to insure alinement thereof with respect to said shank.

70 The base of the switch preferably comprises a punched plate or disk 24 of relatively thin insulating material. Positioned upon the upper face of base 24 are the stationary contacts 25 and 26 and positioned on the lower face of the base are a pair of identically shaped terminal plates 27. As shown 75

each of the contacts 25 and 26 is punched or stamped from relatively thin sheet metal, and I therefore provide the adjacent edges of said contacts with bent portions or ribs 51 and 52. When contacts 25 and 26 are attached to the base the adjacent ribs 51 and 52 provide a groove of predetermined depth therebetween into which the bridging head 22^b of the contactor is adapted to fit,—said head being movable from one side to the other of the rib 52 into and out of engagement with the rib 51.

80 As shown, contact 25 is provided with a rib 51 at opposite edges thereof,—but the additional rib is merely intended to permit assembly of the contact to the base in either of two reverse relations. Contact 26 85

100

is preferably provided with a relatively small perforation to provide a socket or seat for the bridging head 22^b when in off position.

Integral with the contacts 25 and 26 are 5 downwardly projecting pairs of lugs 29, 30 and 35, 36; the lugs 29, 30 being adapted to penetrate registering perforations 31, 32 and 33, 34 in base 24 and one of the terminal plates 27, and the lugs 35, 36 being adapted to penetrate registering perforations 37, 38 and 33, 34 in the base and the other of said terminal plates, the lugs of each pair being then bent outwardly in opposite directions over the terminal plates to secure the respective 10 groups of elements to each other and to the base.

Each of the terminal plates 27 is provided with a tapped opening 41 for cooperation with the usual binding screws 43, the base 20 member being provided with perforations 45 and contacts 25 and 26 being provided with perforations 47 and 48, respectively, to provide clearance for the shanks of said screws.

The slide button 21 is provided with a relatively thin flat portion 21^b which underlies 25 the wall 11 of the frame; said portion 21^b being provided on its lower face with a longitudinal groove or channel 58 which is adapted to accommodate spring 23 and to 30 prevent relative lateral movement therebetween. Intermediate the length of groove 58 is a recess 59 to accommodate the flange or collar 23^a on the spring; and concentric with said recess 59 is a recess 60 within which the 35 shank 22^a of the contactor is adapted to slide.

In attaching the terminal plates 27 I preferably interpose between the same and the base 24 the base portions 53 of a pair of insulating barrier members or wire guards, said 40 base portions 53 having perforations 54, 55 to register with the groups of perforations 31, 32, 45 or 37, 38, 45 in the base 24. Said base portions 53 are preferably of substantially elliptical contour, and extending downwardly at substantially right angles from one 45 curved edge of each is an integral flange 56 which acts as a guard or barrier at the adjacent sides of the respective terminals and their binding screws.

Assuming attachment of the contacts and 50 terminal members to base 24 in the manner aforescribed, and further assuming positioning of the spring and contactor within the slide button 21 and location of the latter 55 within the frame, the switch parts may be assembled as a whole by causing the lugs 18, 19 of the frame sides to penetrate the perforations 61, 62 in base 24, said lugs being then bent outwardly over the base to rigidly and 60 permanently secure the parts with respect to each other.

The switch parts are shown in circuit making position in Figs. 1 and 2, whereas 65 obviously upon movement of button 21 to the right to its opposite extreme position, the

bridging head 22^b is caused to disengage the contact 25.

The multiple circuit controlling switch illustrated in Figs. 4 to 6 is generally similar to that aforescribed, and certain of the aforescribed parts may be utilized in constructing the same. Thus the spring 23 and the associated contactor 22 may be identical with those aforescribed. Duplicate end contacts 26 and terminal plates 27 therefor 70 may likewise be provided. In this form, however, the contactor is required to have two "on" positions and an intermediate "off" position. Accordingly a relatively longer frame 63 is required, the upper wall 64 of said frame having an elongated rectangular perforation to guide and limit travel of the projecting portion 76^a of the actuating slide button 76, the thin base portion 76^b of said button being provided with a longitudinal groove or channel 77, and said button being provided with concentric recesses 78 and 79 similar to those aforescribed.

The insulating base 80, which is of substantially rectangular contour, is provided with groups of perforations 88, 89, 45 and 90, 91, 45 to respectively provide for attachment of end contacts 26 and their terminal plates 27 by means of the lugs 35, 36 of the former, and to provide clearance for the shanks of the 90 binding screws.

The intermediate stationary contact 85 is relatively narrow and is provided in its surface 86 between the ribs 44, 46 at opposite edges thereof with a relatively narrow slot 100 87, the walls of which are adapted to provide a seat for the head 22^b of the contactor in its "off" position. Contact 85 is provided with integral lugs 35, 36 which project downwardly through perforations 92, 93 in base 80 and 105 through perforations 97, 98 in the arms 95, 96 of a substantially U-shaped terminal member 94. The downwardly offset portion 99 of said terminal member is thus adapted to provide sufficient clearance for the shank of its binding screw 43 beneath the insulating base 80, thus obviating any possible interference 110 with the proper movement of the bridging contactor of the switch.

The manner of assembling the switch parts 115 will be apparent from the foregoing description, it being noted that the parallel sides 67, 68 of the frame 63 are each provided at their lower edge with pairs of integral lugs 69, 70 and 71, 72 which register with notches 120 81, 82 and 83, 84 in opposite sides of base 80, the opposed pairs of lugs being bent inwardly toward each other and against the lower face of the base to secure the switch parts in 125 assembled relation.

What I claim as new and desire to secure by Letters Patent is:

1. In an electric switch, in combination, a 130 relatively thin punched base of insulating material, a plurality of stationary contact

- members each comprising a thin metal stamping having a body portion lying flat against the upper face of said base, punched metal terminal plates lying flat against the lower face of said base, said contact members having integral lugs and said base and terminal plates having registering perforations, said lugs penetrating said perforations and being bent over said terminal plates to rigidly secure all of said parts to each other, said terminal plates having tapped openings and binding screws for cooperation therewith, said base and said contact members having registering perforations to accommodate the shanks of said screws, the adjacent ends of said contact members being formed into parallel ribs, and a spring-pressed convex contactor movable selectively into and out of bridging relation to said ribs.
2. In an electric switch, in combination, a relatively thin punched base of insulating material, a plurality of stationary contact members each comprising a thin metal stamping having a body portion lying flat against the upper face of said base, punched metal terminal plates lying flat against the lower face of said base, said contact members having integral lugs and said base and terminal plates having registering perforations, said lugs penetrating said perforations and being bent over said terminal plates to rigidly secure all of said parts to each other, said terminal plates having tapped openings and binding screws for cooperation therewith, said base and said contact members having registering perforations to accommodate the shanks of said screws, the adjacent ends of said contact members being formed into parallel ribs, and a spring-pressed convex contactor movable selectively into and out of bridging relation to said ribs, said contactor being arranged for continuous engagement with one of said contact members and being engageable with a socket or recess in the latter upon movement of the former out of bridging relation.
3. In an electric switch, in combination, a base comprising a flat punched plate of insulating material, spaced sheet metal contact members on one face of said base and sheet metal terminal members on the opposite face of said base, means integral with said contact and terminal members for rigidly securing the same to each other and to said base, each of said contact members being formed of relatively thin material and the adjacent ends thereof having ribs formed therein to provide a groove of predetermined depth therebetween, a contactor having a convex head portion adapted for movement into and out of bridging relation to said contacts, an insulating slide button having a recess, said contactor having a shank portion slidable within said recess, spring means interposed between said button and said contactor to bias the latter into engagement with one or more of said contacts, a sheet metal housing having a slot through which a portion of said button is adapted to extend for limited sliding movement with respect thereto, said housing being adapted to retain said button and said contactor in assembled relation to said base, and means integral with said housing to provide for attachment thereof to a suitable support.
4. In an electric switch, in combination, a base comprising a flat punched plate of insulating material, spaced sheet metal contact members on one face of said base and sheet metal terminal plates on the opposite face of said base, means integral with said contact members and said terminal plates for rigidly securing the same to each other and to said base, an insulating slide button movable across the face of said base, said button having a channeled lower end, an outwardly bowed spring member located within said channel and held thereby against lateral displacement, said button having a centrally located substantially cylindrical recess, said spring member having a perforation registering with said recess, and a contactor having a shank portion penetrating said perforation and slidable within said recess for positioning thereby, said contactor having a convex head to be moved into or out of bridging relation to said contacts upon corresponding movements of said button.
5. In an electric switch, in combination, a base comprising a flat punched plate of insulating material, spaced sheet metal contact members on one face of said base and sheet metal terminal plates on the opposite face of said base, means integral with said contact members and said terminal plates for rigidly securing the same to each other and to said base, an insulating slide button movable across the face of said base, said button having a channeled lower end, an outwardly bowed spring member located within said channel and held thereby against lateral displacement, said button having a centrally located substantially cylindrical recess, said spring member having a perforation registering with said recess, and a contactor having a shank portion penetrating said perforation and slidable within said recess for positioning thereby, said contactor having a convex head to be moved into or out of bridging relation to said contacts upon corresponding movements of said button, each of said contact members being formed of relatively thin material and one of the same having a rib formed therein to resist such movements of said contactor and to increase the degree of compression of said bow spring.
6. In an electric switch, in combination, a base comprising a relatively thin punched plate of insulating material, a plurality of spaced stationary contact members lying flat

- against the upper face of said base, a plurality of terminal members located on the lower face of said base, said base and said terminal members having registering perforations and 5 said contact members having integral lugs penetrating said perforations and bent over said terminal members to secure said parts in assembled relation, two of said contact members having ribs formed at the adjacent 10 ends thereof, the third contact member being located between said other contact members and having ribs formed at each end thereof, all of said ribs being arranged in parallelism with each other to provide grooves of predetermined 15 depth therebetween, and binding screws having threaded engagement with each of said terminal members, said base and said end contact members having registering perforations to accommodate the shanks of certain of said 20 binding screws, the intermediate terminal member having a downwardly offset portion whereby the shank of its binding screw is accommodated below said base. 25 7. In an electric switch, in combination, a base comprising a relatively thin punched plate of insulating material, a plurality of spaced stationary contact members lying flat against the upper face of said base, a plurality of terminal members located on the lower face of said base, said base and said terminal members having registering perforations and said contact members having integral lugs penetrating said perforations and 30 bent over said terminal members to secure said parts in assembled relation, two of said contact members having ribs formed at the adjacent ends thereof, the third contact member being located between said other contact 35 members and having ribs formed at each end thereof, all of said ribs being arranged in parallelism with each other to provide grooves of predetermined depth therebetween, binding screws having threaded engagement with each of said terminal members, said base and said end contact members having registering perforations to accommodate the shanks of certain of said binding screws, the intermediate terminal member having a downwardly offset portion whereby the shank of its binding screw is accommodated below said base, and insulating barriers located between the respective terminal members, said barriers each comprising a flat base portion to be clamped between one of said end terminal members and the base, each of said base portions having an integral flange extending downwardly from a curved edge thereof. 40 45 50 55 60 65 70 75 80 85 90 95 100 105 110 115 120 125 130 8. In an electric switch, in combination, a base comprising a relatively thin punched plate of insulating material, a plurality of spaced stationary contact members lying flat against the upper face of said base, a plurality of terminal members located on the lower face of said base, said base and said terminal members having registering perforations and said contact members having integral lugs penetrating said perforations and bent over said terminal members to secure said parts in assembled relation, two of said contact members having ribs formed at the adjacent ends thereof, the third contact member being located between said other contact members and having ribs formed at each end thereof, all of said ribs being arranged in parallelism with each other to provide grooves of predetermined depth therebetween, binding screws having threaded engagement with each of said terminal members, said base and said end contact members having registering perforations to accommodate the shanks of certain of said binding screws, the intermediate terminal member having a downwardly offset portion whereby the shank of its binding screw is accommodated below said base, and insulating barriers located between the respective terminal members, said barriers each comprising a flat base portion to be clamped between one of said end terminal members and the base, each of said base portions having an integral flange extending downwardly from a curved edge thereof.

- between one of said end terminal members and the base, each of said base portions having an integral flange extending downwardly from a curved edge thereof, a contactor adapted for continuous engagement with said intermediate contact and movable in opposite directions over the ribs formed on the latter to effect bridging engagement with said end contacts selectively, said contactor having a convex bridging portion and a shank, a slide button having a recess within which said shank is adapted to slide, a plate spring interposed between said bridging portion and said button and bowed downwardly to bias said bridging portion in a corresponding direction, a substantially inverted U-shaped frame rigidly secured to said insulating base and engaging said button to retain the latter and said contactor in assembled relation to said insulating base. 70
10. In an electric switch, in combination, a base comprising a relatively thin punched plate of insulating material, a plurality of spaced stationary contact members lying flat against the upper face of said base, a plurality of terminal members located on the lower face of said base, said base and said terminal members having registering perforations and said contact members having integral lugs penetrating said perforations and bent over said terminal members to secure said parts in assembled relation, two of said contact members having ribs formed at the adjacent ends thereof, the third contact member being located between said other contact members and having ribs formed at each end thereof, all of said ribs being arranged in parallelism with each other to provide grooves of predetermined depth therebetween, binding screws having threaded engagement with each of said terminal members, said base and said end contact members having registering perforations to accommodate the shanks of certain of said binding screws, the intermediate terminal member having a downwardly offset portion whereby the shank of its binding screw is accommodated below said base, insulating barriers located between the respective terminal members, said barriers each comprising a flat base portion to be clamped between one of said end terminal members and the base, each of said base portions having an integral flange extending downwardly from a curved edge thereof, a contactor adapted for continuous engagement with said intermediate contact and movable in opposite directions over the ribs formed on the latter to effect bridging engagement with said end contacts selectively, said contactor having a convex bridging portion and a shank, a slide button having a recess within which said shank is adapted to slide, a plate spring interposed between said bridging portion and said button and bowed downwardly to bias said bridging portion in a corresponding direction, a substantially inverted U-shaped frame rigidly secured to said insulating base and engaging said button to retain the latter and said contactor in assembled relation to said insulating base, said button having a portion projecting upwardly through a slot in said frame, and said slot having end walls to limit the sliding movement of said button. 75
11. In a device of the character described, the combination with an insulating base, of a punched metal terminal plate secured thereto, and an insulating barrier member comprising a perforated flat portion to be clamped between said terminal plate and said base, said flat portion having an integral vertical flange extending from a curved edge thereof. 80
12. In an electric switch, in combination, a punched plate of insulating material, contact members each having lugs penetrating said plate, terminal members secured to said plate by said lugs, a metal frame of substantially inverted channel shape rigidly secured to said plate, said frame having a rectangular slot in the upper wall thereof, an insulating button having a portion slidably engaging the lower surface of said upper wall and a portion engageable with the walls of said slot to guide said button and to limit endwise movement of the latter, said button having a channel in the lower face thereof, a bow spring located within said channel and restrained thereby against lateral displacement, said button having concentrically arranged 90 cylindrical recesses, said bow spring having a perforation and an upwardly extending flange surrounding said perforation, said flange being accommodated by the larger of said recesses, a contactor having a shank penetrating said perforation and slidably within the other of said recesses, said shank being adapted to restrain said spring against substantial endwise movement within said channel, and a convex head portion on said contactor against which said spring is adapted to bear, said head portion being adapted for continuous engagement with one of said contact members and being movable selectively into and out of engagement with another of said contact members. 100
